UNITED STATES PATENT OFFICE.

FRANK W. MERRICK, OF BOSTON, MASSACHUSETTS.

TAKE-UP FOR SEWING-MACHINES.

SPECIFICATION forming part of Letters Patent No. 707,145, dated August 19, 1902.

Application filed August 11, 1899. Serial No. 726,871. (No model.)

To all whom it may concern:

Be it known that I, FRANK W. MERRICK, a citizen of the United States, residing at Boston, in the county of Suffolk, State of Massachusetts, have invented a certain new and useful Improvement in Take-Ups for Sewing-Machines, of which the following is a specification, reference being had therein to the accompanying drawings.

10 I have illustrated in the accompanying drawings the best form in which I have thus far embodied my invention.

It should be understood at the outset that I do not confine myself to the precise particulars of construction and arrangement which are shown in the said drawings and referred to in the course of the following description, inasmuch as in many respects the details may vary.

20 The essential features of the invention are clearly defined in the claims at the close of this specification.

Having reference to the drawings, Figure 1 is a partly-broken-out side elevation mainly intended to show the head and part of the arm or gooseneck of a sewing-machine and to illustrate the application thereto of a take-up embodying the invention, the thread-carrier mechanism being also represented in order 25 that the relations between the same and the take-up may appear. Fig. 2 is a partly-sectional top or plan view mainly intended to show the take-up and thread-carrier mechanism. Fig. 3 is a view in vertical section on the plane indicated by the dotted line 3 3 in Fig. 2 looking in the direction indicated by the arrows near the ends of such line. Fig. 4 is a view in vertical section on the plane indicated by the dotted line 4 4 in Fig. 2 looking 30 in the direction indicated by the arrows near the ends of such line. Fig. 5 is a view mainly in vertical section on the plane indicated by the dotted line 5 5 in Fig. 1 looking in the direction indicated by the arrows near 35 the ends of such line.

40 Having reference to the drawings, 1 designates the arm or gooseneck of the frame of a sewing-machine. 2 is the head. 3 is a rotating shaft mounted in bearings in the said arm, one of the said bearings being represented at 4, Fig. 1. 5 is the awl, working from above the material to be sewed; 6, the

presser-bar; 7, the presser-foot; 8, the hooked needle, working upwardly from below, and 81 the work-rest. All of these parts are as usual 55 in sewing-machines and in practice are operated in any approved manner.

9 is the thread-carrier, which, if desired, may be operated in practice in any approved manner. Herein I have represented the same 60 combined with the particular operating devices therefor which are claimed in my application for United States Letters Patent filed August 11, 1899, Serial No. 726,869.

a designates the thread.

10 and 11 are thread-guiding pulleys or rolls over which the thread passes on its way from the source of supply to the thread-carrier 9. For convenience the pulley 11 is mounted on the arm 13, to which thread-carrier 9 is attached, while pulley 10 is mounted upon a pin 14, which is supported directly by the arm 1. (See Fig. 5.)

My improved take-up comprises, essentially, in its simplest form a rotary carrier, 75 one or more pins applied to said carrier, and means to occasion a relative shift between the path of rotation of the pin or pins and the path of the thread to cause the pin or pins to become engaged with the thread in the 80 rotation of the carrier to effect the taking up of the thread. I employ two pins 15 15 by preference, as in the illustrated embodiment of the invention, the said pins being disposed diametrically opposite each other on the carrier 85 therefor. For ease of action upon the thread and to take the wear these pins are in practice surrounded by sleeves 16 16. The carrier comprises herein the central sleeve 17 and the heads 18 and 19 thereon. The take-up pins 15 15 are made fast to the head 19, and they and the sleeves 16 16 thereon are fitted to bushings 20 20, which are placed in 90 openings in the head 18. The sleeve 17 of the carrier surrounds the shaft 21, the ends of 95 which have fitted thereto bushings 22 22, fitting openings in opposite sides of the arm 1 and secured therein by clamping-screws 221 221. For the purpose of rotating the carrier a spur-pinion 23 is fixed upon sleeve 17, the 100 said spur-pinion meshing with a carrier or intermediate 24, which latter in turn meshes with the spur-gear 25, fast on the short shaft 26. Shaft 26 is mounted in a bearing at 27

in the arm 1 and has fast thereon the bevel-gear 28, meshing with the bevel-gear 29 on shaft 3. Through the connections described the take-up device is rotated from the shaft 3.

5 An important characteristic of my take-up devices is the fact that the carrier is caused to make two or more complete revolutions to each turn of the machine. The shaft 3 from which the carrier is driven makes one revolution to each turn of the machine, and the required increased rate of speed of the carrier is secured by suitably proportioning the described motion - transmitting gearing by means of which the carrier is rotated from 15 shaft 3. In the present embodiment of the invention the relative speed that is communicated to the rotary take-up is double that which would be required in order to bring the same in action for each stitch formation. 20 By speeding up the take-up device in the manner just explained to a multiplied extent with reference to the action of the stitch-forming devices the excess of speed which thereby is secured causes the take-up to act upon the 25 upper thread with the requisite promptness in drawing up a stitch and within the allotted portion of a turn of the machine, which portion thus is enabled to be reduced to a minimum. On account of the relatively multiplied speed of rotation of the take-up device 30 every other turn thereof is an extra or idle one—*i. e.*, it occurs when there is no stitch to be tightened up—but it is preferred that this should be the case, inasmuch as it is much 35 easier to maintain the take-up in revolution at a uniform high rate of speed than it is to alternately speed up and then retard the motion of the take-up.

In the present instance the engagement of 40 the take-up pins with the thread is brought about through shifting the said pins into the path of the thread at the required time in the working of the machine. In order to permit the required shift of the said pins, the head 45 19 is fitted to the exterior of the sleeve 17 with capacity to move lengthwise of the latter. Head 18 is fixed to the carrier. A convenient means of occasioning the movement of the head 19 and pins carried thereby relatively to the fixed head 18 and the path of 50 the thread comprises the arms 30, provided with pins entering the groove 31 of the hub of the movable head 19, the said arms forming part of a rocker 32. The said rocker has 55 connected therewith a link 33, that is provided with a strap fitting an eccentric 34 on shaft 3. The path of the thread between the pulleys or rolls 10 and 11 is close against the outer face of the fixed head 18 and below the prolongation of the sleeve 17, the said prolongation having applied thereto the bushing 35 to receive the wear that is occasioned by the thread. So long as the pins 15 15 and their sleeves 16 16 are retracted relatively to the 60 65 said fixed head they do not engage with the thread. When, however, the movable head 19 is carried toward the fixed head 18, the

pins and their sleeves are caused to project at the outer side of the fixed head. They now, in the rotation of the carrier, engage 70 with the thread at points on opposite sides of the center of rotation and immediately wrap the thread around themselves in the form of two loops, which are drawn out in opposite directions. The pins draw upon the thread 75 through approximately half a revolution of the carrier, and then the loops of thread are cast off from the exteriors of the sleeves 16 16 as the latter are drawn reversely through the bushings 20 20. The pins 15 15 remain retracted relatively to the fixed head 18, and therefore incapable of engaging with the thread during the extra or idle revolution of the take-up device. In order to cause them to be projected into position to engage the 80 thread only in the alternate revolutions of the carrier, the movement of the rocker which shifts the movable head 19 is derived from shaft 3, as aforesaid, the said shaft rotating at one-half the speed of the take-up device. 85 90

For the purpose of preventing the loops of thread from flying when they are shed or cast off from the sleeves 16 16 in the retraction of the pins 15 15 a yielding follower is employed adjacent the outer face of the fixed head 18. 95 The said follower is constituted herein by a disk 36, which is acted upon by a spring 37, that tends to bear the follower toward the fixed head 18. The face of the follower is recessed, as at 38 38 in dotted lines in Fig. 5, 100 to fit over the ends of the bushings 20 20 and pins 15 15. The spring 37 surrounds the hub of the follower and is compressed between the disk and a nut 39. The latter is applied to an externally-threaded bushing 40, which is 105 applied to shaft 21 between the end of sleeve 17 and the adjacent bearing 22, a lock-nut 41 being applied to bushing 40, also to secure nut 39 after it has been adjusted to give the desired degree of tension to spring 37. One 110 portion of bushing 40 extends over the prolongation of sleeve 17. The hub of the follower is sleeved upon the exterior of bushings 35 and 40. The bushing 40 is held from movement relatively to sleeve 17 by means of 115 a key 42, which latter serves also as a spline for the follower.

Adjustment of the amount of thread taken up by the action of the take-up is effected by moving the pins 15 15 toward or from the center of rotation of the carrier. In order to permit of a radial movement of the said pins, the openings in head 18, which receive the bushings 20 20, and those in head 19, which receive the pins, are formed as radial 125 slots, as shown in the case of the latter at 43 43, Fig. 4.

For the purpose of enabling the pins 15 15 to be adjusted simultaneously and to equal extents in either direction I combine there- 130 with the adjusting-plate 44. The latter is formed with cam-surfaces to act on the said pins. Herein the said cam-surfaces are constituted by duplicate or similar eccentric

curved slots 45 45, (see Fig. 4,) through which the pins pass. The said plate is at the outer side of the movable head 19 and is clamped in position and to the said movable head by means of the nuts 46 46, by which the pins 15 15 themselves are made fast.

The drawings show the thread-carrier mechanism which is claimed in my application aforesaid for United States Letters Patent.

10 The said mechanism comprises, essentially, an inner oblong open frame or yoke 47, which is formed or provided with the arm 13, to which the thread-carrier 9 is applied, an outer similar oblong open frame or yoke 48, a link 49, and an eccentric 50 or shaft 3, to which eccentric is fitted the strap with which the link 49 is formed or provided. One end of the outer yoke 48 is pivoted to the head 2 by means of center screws 51 51, passing through 15 prolongations of the said outer yoke and finding seats or bearings on the front and rear sides of the head. The yoke 48 is adapted to swing vertically about the axes of the said center screws. The inner yoke 47 is pivoted 20 at its opposite ends to the cross-bars of the outer yoke by means of center screws at 52 52 and is adapted to swing transversely about the axes of the said center screws. The lower end of the link 49 is connected pivotally with 25 the opposite side bars of the inner yoke 47 by means of center screws at 53 53. The ascending and descending movements given to the link 49 by the action of the eccentric 50 serve to rock the two yokes about the axes of 30 the center screws 51 51, thereby swinging the free end of the thread-carrier 9 to the right and left in Fig. 1 with reference to the needle 8. The transverse movements that are communicated by the said eccentric to the said 35 40 link serve to rock the yoke 47 transversely within the outer yoke 48 upon the center screws 52 52, thereby causing the free extremity of the thread-carrier to partake of a forward and rearward movement as it swings. 45 Thus the thread-carrier is caused to make a complete circuit around the needle at every turn of the machine.

The foregoing construction of thread-carrier mechanism has been devised with especial reference to being combined with the herein-described form of take-up. The heads, &c., of the latter fit within the opening of the inner yoke, while the side bars of both yokes are dropped or bent downwardly at the middle of their length, so as to clear the sleeves, bearings, and other parts pertaining to the take-up at both sides of the heads.

I claim as my invention—

1. A rotary take-up comprising, essentially, 60 a carrier making successive complete rotations in the same direction, means to rotate said carrier, diametrically opposite pins with which said carrier is provided, and means to occasion intersection of the path of the thread by that of the pins, whereby oppositely-extending loops are formed in the thread by the rotation of the pins, and subsequent separa-

tion of the said paths, whereby the said loops are released during the continued rotation of the carrier, substantially as described.

70

2. A rotary take-up comprising, essentially, a carrier, means to rotate the same, diametrically opposite pins with which said carrier is provided, means to project said pins transversely across the path of the thread, whereby 75 the engagement of the pins with the thread operates to form oppositely-extending loops therein, and subsequently retract said pins transversely out of the said loops to release the latter, substantially as described.

80

3. A rotary take-up comprising, essentially, a carrier, means to rotate the same, diametrically opposite pins with which said carrier is provided, means to occasion intersection of the path of the thread by that of the pins, 85 whereby oppositely-extending loops are formed in the thread by the rotation of the pins, and subsequent separation of the said paths, whereby the said loops are released during the continued rotation of the carrier, and 90 a yielding follower to prevent flying of the thread after its disengagement from the pins, substantially as described.

85

4. A take-up for sewing-machines, comprising a rotary carrier, oppositely-located thread-engaging pins engaging with the thread to form oppositely-extending loops, means to project said pins to engage with the thread and retract the same to free the thread, and the yielding follower alongside said carrier.

95

5. A rotary take-up for sewing-machines, comprising oppositely-located thread-engaging pins engaging with the thread to form oppositely-extending loops, a head through which said pins work, a second head with 105 which the said pins are connected, and operating means whereby projection of the said pins relatively to the head first mentioned is occasioned to effect their engagement with the thread intermittently.

110

6. A take-up for sewing-machines comprising a rotary carrier having a fixed head, oppositely-located thread-engaging pins working through said fixed head, a movable head with which the said pins are connected, and means to adjust the said pins toward and from each other, and means to operate the said movable head and thereby project and retract the thread-engaging ends of the said pins at the side of the fixed head.

115

7. A take-up for sewing-machines, comprising a rotary carrier having radial guides, oppositely-located thread-engaging pins applied to the said guides, a head with which the said pins are connected, an adjusting-disk having 125 cam-surfaces to regulate the distance of the said pins from each other, and means to operate the said head and thereby move the said pins endwise to engage and disengage the thread.

120

8. A take-up for sewing-machines, comprising a rotary carrier having a fixed head, oppositely-located thread-engaging pins working through said fixed head, a movable head

130

with which the said pins are connected, means to operate the said movable head and thereby project and retract the thread-engaging ends of the said pins at the side of the fixed head, 5 and the adjusting-plate having the eccentric-slots through which the said pins pass.

9. The rotary take-up consisting of the carrier comprising essentially the fixed head, the oppositely-located pins working through 10 openings in the said fixed head, and the movable head with which the said pins are connected, means to rotate the said carrier, the rocker in operative connection with the said movable head, means to operate the rocker, 15 and the spring-pressed follower at the side of the said fixed head.

10. The rotary take-up consisting of the

carrier comprising essentially the sleeve, the head fixed to the said sleeve, the oppositely-located pins working through openings in the 20 said fixed head, the movable head on the said sleeve having the said pins connected therewith, means to rotate the said carrier, the rocker in operative connection with the said movable head, means to operate the rocker, 25 and the spring-pressed follower splined to the said sleeve.

In testimony whereof I affix my signature in presence of two witnesses.

FRANK W. MERRICK.
